2,098,563

APPARATUS FOR MAKING WELT UNITS

William C. Card, Jr., Winthrop, Mass., assignor
to Compo Shoe Machinery Corporation, Boston,
Mass., a corporation of Delaware

Application August 26, 1936, Serial No. 97,908

12 Claims. (Cl. 112—46)

This invention relates to machines for forming a welt unit useful in the manufacture of certain types of shoes.

In a copending application, Serial No. 38,685, filed August 31, 1935, there is described and claimed a novel form of shoe in which a leather welt is stitched to a fabric fastening strip to form a welt unit, the welt portion of which is sewed around the edge of an outsole and the fastening strip portion of which is cemented to the bottom of a lasted upper. This welt unit per se, which preferably has a doubled edge on the fabric strip forming a rib to which the welt is attached, is claimed in another copending application, Serial No. 50,070, filed November 16, 1935.

An object of this invention is to provide a novel apparatus for making such welt units.

More particularly, objects of the invention are to provide an apparatus for doubling the edge of a fabric fastening strip and sewing a welt to such doubled edge, and for thereafter undoubling the strip to position it properly for eventual cementing to a lasted upper.

Further objects are to provide such an apparatus utilizing a more or less conventional sewing machine having in combination novel attachments enabling it to perform the functions needed to make the herein contemplated article, in which such attachments are simple, rugged, and readily attachable with the machine on which they are mounted.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the claims.

For a fuller understanding of the nature and objects of the invention reference should be had to the following detailed description taken in connection with the accompanying drawings, in which:

Fig. 1 is a horizontal sectional view taken along line 1—1 of Fig. 2 and showing certain sewing machine attachments embodying the principles of this invention, portions of the machine itself being substantially broken away better to illustrate the attachment construction;

Fig. 2 is a side elevation of a sewing machine assembly made in accordance with the present invention;

Fig. 3 is a fragmentary transverse sectional view corresponding with line 3—3 of Fig. 2;

Fig. 4 is a fragmentary transverse sectional view on an enlarged scale corresponding with line 4—4 of Fig. 1;

Fig. 5 is a fragmentary perspective view on an enlarged scale of the portion of the mechanism adjacent to the stitching needle;

Fig. 6 is a fragmentary front elevation on an enlarged scale showing details of the mechanism.

Fig. 7 is a transverse sectional view across a completed welt unit; and

Fig. 8 is a fragmentary perspective view corresponding to Fig. 5, but showing another form of mechanism.

The present apparatus is especially designed to form a stitched welt unit such as that illustrated in Fig. 7. Referring first to that figure, it will be seen that the unit comprises a welt preferably of leather *a*, which preferably has a stitching groove *b* on its flesh side and a bevelled edge on its opposite or grain side. A fabric fastening strip *c* having a doubled fold at *d* which forms a downwardly extending attaching rib lying closely adjacent to the bevelled corner and inner edge of the welt, is stitched to the welt by means of stitching *e* which passes through the doubled fold or attaching rib. The fabric *c* provides a cementable area on its upper surface which is adapted to be stuck against the bottom of a lasted upper, and it will be noted that this cementable surface extends both inwardly and outwardly from the stitching *e*.

In the construction of a shoe the welt *a* is first stitched around the edge of an outsole and the shoe bottom thus formed is attached to the bottom of the lasted upper by cementing strip *c* thereto as mentioned above. Since downward kicking or scuffing forces which may be applied to the outsole are transmitted to the cemented strip through stitches *e*, it is of advantage to have the cemented portions of the strip located both inwardly and outwardly from the stitches as such a construction makes it more difficult to peel apart the cemented bond. The welding *a*, and strip *c*, are adapted to be fed from reels of indefinite length and formed into a welt unit strip of indefinite length which may later be cut into sections of appropriate length for attachment to a given outsole.

Referring more particularly to the remaining drawings, the apparatus for forming such a continuous welt unit comprises a sewing machine, generally designated 10, which may be of any suitable or conventional type adapted to form any suitable kind of permanent stitch, and which may

be equipped and modified to perform the functions herein described. For example, a Singer class 7-31 sewing machine is found to be well suited to the purpose. The machine has a driven stud shaft 11, and suitable mechanism for driving the needle 12 therefrom. In the form shown in Figs. 1 to 6 a reciprocable presser foot 13 is also provided and is mounted for vertical up and down movement in timed relation with the needle 12 in the usual or any other suitable manner. This presser foot is of special construction, as will hereinafter appear. The thread feeding mechanism, spools, bobbins, etc. may all be of conventional form.

15 A reel 14 for the welting *a* is mounted above the machine and the continuous welt strip is fed downwardly through a guide bracket 15 toward the in-feed side of the needle. A similar reel 14' is positioned beneath the machine and a 20 continuous strip of fabric *c* is likewise led toward the in-feed side of the needle through a suitable slot 14'' provided in the machine base. The fabric strip is threaded through a suitable folder 16. As shown in Fig. 5, this comprises a 25 U shaped outer plate and an inner straight tucking plate 17 spaced therefrom by shims, one of which, numbered 18, forms a guiding edge for the fabric strip. This strip is of determined width, usually about three-quarters of an inch, 30 and the guide shim 18 accordingly determines just how much of the inner edge is doubled over by the folder. As illustrated, this edge is doubled back a fairly short distance, say one-fourth the width of strip *c*, in order to provide adequate 35 material for the ultimately formed rib *d* and to provide a cementable surface located outwardly as well as inwardly from the attaching stitches. The folder 16 is located just ahead of the stitching needle 12 and positions the strip with respect thereto. The strip is additionally guided adjacent to such needle by an adjustably fixed 40 abutment 19. The welt *a* is fed from bracket 15 beneath the presser foot 13 which, as best shown in Fig. 6, has a guide shoulder 20 on its 45 under side, which is adapted to engage an edge of the welt to register it with the double fabric strip. The guide abutment 19 also has a portion engageable against the inner edge of the welt to aid in maintaining this registry. The needle is 50 so located with respect to these registered parts as to stitch along an inseam *e* (Fig. 6), thus joining the doubled attaching rib to the inner edge of the welt.

The feeding of the welt and strip is preferably 55 effected by a pair of rollers 21 and 22 which also have the function of undoubling the doubled fabric strip to the flat cement receiving condition illustrated in Fig. 7. However, it is contemplated that separate material feeding and 60 doubling means may be provided. The rollers 21 and 22 are provided with opposed cylindrical surfaces 23 and 24 respectively, and opposed conical surfaces 25 and 26 respectively. The welt *a* passes between these conical surfaces and the 65 fabric strip is passed between the cylindrical surfaces, and such surfaces are arranged at an angle to undouble the free portion of strip *c* and flex and pull it beyond its original position so that any tendency to spring back to its stitched 70 doubled condition is largely overcome, and so that the inseam *e* is pulled around into the position shown in Fig. 7.

The roller 21 is freely rotatable on a short stud shaft 27 which is mounted on a swinging 75 bracket 28 (Fig. 4) pivotally mounted on the

machine base. A fixed bracket 29 is located just above the swinging bracket and carries a double gear housing 30. A stud shaft 31 extends from the housing 30 to the roller 22 and has the latter keyed to it. A spring bolt 32 passes through the fixed bracket 29 and the swingable bracket 28 and a compression spring 33 is seated between bracket 28 and a head on the lower end of the bolt to give the brackets and the rollers carried thereby a normal bias toward each other.

The shaft 31 carrying roller 22 has a gear 34 fixed to it which meshes with a gear 35 (Fig. 2) which is located within the housing 30 and is carried by a drive shaft 36 mounted between the housing 30 and a bracket 37 at the other end of the machine. This drive shaft is intermittently driven from the main stud shaft 11 to impart feeding movement to the roller 22 in timed relation with the parts associated therewith. Mechanism for effecting this comprises a cam 38, shown in Fig. 3, fixed to the shaft 11. A lever 39 is pivotally mounted on a bracket 40 at 41, and has a roller 42 riding against the cam 38. The lower end of the lever 39 has a pivotal connection at 43 with a link 44. The pivotal connection 43 is adapted to be adjustably moved along a slot 45 in the lever 39 in order to vary the throw of link 44. The other end of link 44 is pivotally attached to a rocker arm 46 freely mounted on the shaft 36. A pawl 47 is pivotally mounted on the rocker arm 46 and has its nose spring biased into contact with a ratchet wheel 48 fixed to the drive shaft 36. It will be seen that this mechanism is adapted to impart intermittent driving movement to the shaft 36 from the constantly rotating cam 38. The amount of feeding movement may be controlled at 43 and 45 to correspond with the rate of stitching as determined by the length of the individual 40 stitches.

In operation, once the fabric strip *c* has been threaded through the folder 16 and registered with the guided welt *a*, these parts may be moved by hand until they reach the feed rollers 21 and 22, where they may be inserted and clamped in proper undoubling position between such rollers. As soon as these materials are thus clamped between the feeding rollers, the operation of the 50 sewing machine shaft 11 will thereafter automatically effect all of the movements needed to form a completed welt unit.

In Fig. 8 another form of guide means is shown. Here instead of using a reciprocable 55 presser foot having a guide shoulder on its under side, a guide slot 49 exactly accommodating the welt *a* is provided above the folder 16. This guide slot may be formed by means of an angle plate 50 adjustably mounted at 51. The slot 49 is suitably aligned with the fabric strip guide plate 18 to effect the desired registry between the sewn parts, and this registry is further aided in the vicinity of the stitching needle by opposed abutments 52 and 53, the latter being 65 a continuation of a guiding side wall of the welt slot.

In both forms, the folding mechanism is mounted on an inclined or wedge shaped support 53 against which the welt unit rests during the stitching operation. The needle 12, of course, clears this support, which may be cut down in the vicinity of the needle for the sake of clearance, if desired or needed.

It will be seen that an apparatus has been pro- 75

vided which is well suited to fulfill its intended functions. Since certain changes may be made in the above construction and different embodiments of the invention could be made without departing from the scope thereof, it is intended that all matter contained in the above description or shown in the accompanying drawings shall be interpreted as illustrative and not in a limiting sense.

10 It is also understood that the following claims are intended to cover all of the generic and specific features of the invention herein described, and all statements of the scope of the invention which, as a matter of language, might be said to fall therebetween.

15 Having described my invention, what I claim as new and desire to secure by Letters Patent is:

1. A machine for sewing welt units comprising means for doubling a fabric fastening strip, 20 means for stitching it to a welt, and means for feeding said welt and strip past said stitching means and for undoubling said strip.

2. A machine for sewing units comprising a stitching needle, means for doubling an edge of a 25 fabric fastening strip, means for positioning said doubled edge in registry with one edge of a welt beneath said needle, means for operating said needle to stitch said parts together, means for feeding said welt and strip beneath said needle and thereafter undoubling said strip.

3. A machine for sewing welt units comprising a folder for forming a doubled attaching rib along an edge of a fabric fastening strip, a stitching needle, means for positioning said doubled 35 rib along an edge of a welt beneath said needle, means for driving said needle, opposed feed rollers having portions for engaging said welt and strip to undouble the latter after stitching, and driving connections between said rollers and said needle driving means.

40 4. A machine for sewing welt units; comprising means for doubling a fabric fastening strip, means for stitching it to a welt, opposed feed rollers having portions for engaging said welt and strip to undouble the latter after stitching, and means for driving said rollers and stitching means in timed relation.

45 5. A machine for sewing welt units, comprising means for doubling a fabric fastening strip, means for stitching it to a welt, opposed feed rollers having peripheral portions for engaging said welt and other peripheral portions for engaging said strip after stitching; said roller portions being arranged at an angle with respect to each other to undouble said strip and flex it back beyond its initial position, and means for driving said stitching means and rollers.

6. A machine for sewing welt units, comprising

stitching means, a folder positioned ahead of said means for doubling the edge of a fabric fastening strip into a rib, a guide slot for a welt adjacent said folder, said folder and slot being arranged to register the doubled edge of said strip and the inner edge of said welt beneath said stitching means, and means for driving said stitching means to attach said welt edge and rib.

5 7. A machine for forming welt units, comprising a folder for forming a doubled rib on a fabric 10 fastening strip, means for registering a welt with said rib, and means for stitching said welt to both folds of said rib.

8. A machine for forming welt units, comprising a folder for forming a doubled rib on a fabric 15 fastening strip, means for registering a welt with said rib, and means for stitching said welt to both folds of said rib, and means for thereafter undoubling the strip.

9. A machine for forming welt units, comprising a folder for forming a doubled rib on a fabric 20 fastening strip, means for registering a welt with said rib, means for stitching said welt to both folds of said rib, and opposed rollers for thereafter engaging said welt and strip to straighten 25 the latter out from its doubled position.

10. A machine for forming welt units, comprising a folder for forming a doubled rib on a fabric fastening strip, means for registering a welt with said rib, means for stitching said welt to both 30 folds of said rib, opposed relatively movable rollers for thereafter engaging said welt and strip to straighten the latter out from its doubled position, and spring means giving said rollers a normal bias toward each other.

35 11. A machine for forming welt units, comprising a folder for forming a doubled rib on a fabric fastening strip, means for registering a welt with said rib, means for stitching said welt to both folds of said rib, opposed relatively movable rollers for thereafter engaging said welt and strip to straighten the latter out from its doubled position, spring means giving said rollers a normal bias toward each other, and means for driving said rollers and stitching means in timed 40 relation to impart feeding movement to said welt and strip.

45 12. A means for making continuous welt units, comprising stitching means, a reel for a continuous 50 band of leather welting, a folder between said fabric holding reel and said stitching means for doubling an edge of said strip, means guiding said welting into registered overlying relation with the doubled edge of said strip, and means for driving said stitching means to sew said welt and said doubled edge.

WILLIAM C. CARD, JR.
